CLAIM

The ornamental design for a refrigerator, as shown and described.

DESCRIPTION

FIG. 1 is a front and right side perspective view of a refrigerator according to the invention.

FIG. 2 is a front elevational view thereof according to the invention.

FIG. 3 is a rear elevational view thereof according to the invention.

FIG. 4 is a right side view thereof according to the invention, the left side view being a mirror image.

FIG. 5 is a top plan view thereof according to the invention.

FIG. 6 is a bottom plan view thereof according to the invention; and,

FIG. 7 is a perspective view of the design showing the doors in an open position according to the invention.

The broken lines shown in the drawing disclosure are for illustrative purposes only and form no part of the claimed design.
